UNITED STATES PATENT OFFICE.

MILO E. RICE, OF KANSAS CITY, MISSOURI.

ARTIFICIAL LIMB.

1,271,771.

Specification of Letters Patent.

Patented July 9, 1918.

Application filed September 6, 1917. Serial No. 190,276.

To all whom it may concern:

Be it known that I, MILO E. RICE, a citizen of the United States, and a resident of Kansas City, in the county of Jackson and State of Missouri, have invented certain new and useful Improvements in Artificial Limbs, of which the following is a specification.

This invention relates to artificial limbs, and more especially to knee joints therefor, and has for its object to produce a knee bearing connection susceptible of use on artificial limbs for knee amputations or for what are known as upper amputations.

15 A further object is to produce a knee joint for actuation under the pull of a suspender, to swing the lower limb or member forward and for coöperation with the upper member in arresting such forward movement when 20 the leg as a whole is straightened.

A still further object is to produce a simple, cheap, light and strong knee joint connection, serviceable on artificial limbs of minimum weight.

25 With these objects in view the invention consists in certain novel and peculiar features of construction and organization of parts as hereinafter described and claimed; and in order that the same may be fully 30 understood reference is to be had to the accompanying drawing, in which:

Figure 1, is a side elevation of an artificial leg equipped with a knee joint embodying my invention.

35 Fig. 2, is an enlarged horizontal section taken on the line II—II of Fig. 1.

Fig. 3, is a detail perspective view of the preferred form of knee joint connection for use for upper amputations.

40 Fig. 4, is an enlarged vertical section of the upper end of the same.

Fig. 5, is a fragmentary side elevation of an artificial leg equipped with the preferred type of knee joint for what are known as 45 knee amputations or amputations so close to the knee as to render it impractical to employ the cross bolt connections shown by Figs. 2 and 4.

Fig. 6, is a horizontal section on the line 50 II—IV of Fig. 1, but lacking the cross bolt of Fig. 2.

In the said drawing, where like reference characters identify corresponding parts in all of the figures, 1 indicates the upper or 55 thigh member of an artificial leg, and 2 the lower limb or member of such leg, the lower

end of the upper member fitting the upper end of the lower member in such manner as to be capable of assuming the angular positions necessary in walking and in occupying a sitting position.

Secured to and projecting slightly upward from the side portions of the lower member are metal straps 3 provided with forwardly projecting arms 4 which preferably curve so as to conform approximately to the curvature of the leg, and said arms 4 are braced by depending arms 5 secured to the lower member 2. For use on legs for upper amputations it is preferable to connect the straps 3 by a cross bolt 6 extending pivotally through the upper member, the use of this cross bolt being common on legs for upper amputations. The cross bolt preferably comprises a tube extending through the straps 3 and engaged by headed bolts 7, as shown most clearly in Fig. 4. If preferred however upper straps 8 may be secured to the upper member 1, and pivotally connected or hinged to the upper end of the straps 3 in any suitable manner, as this type of construction is well known and in common use, it being understood however that the use of the cross bolt is impracticable in amputations at or very close to the knee without unduly lengthening the upper or thigh member.

The arms 4 are provided at their outer sides with lugs or buttons 9 for engagement by the lower ends of flexible side straps 10 connected to the lower ends of flexible straps 11 which may extend over the shoulders of the wearer and constitute a suspender. In a suspender of this type, provision for elasticity must be made so that it shall be tensioned when the lower member of the leg swings to the rear relatively speaking, and thus be enabled by an upward pull on said arms 4, to utilize the latter as levers in returning the lower limb or member to normal position. In this connection it will be apparent that when the wearer is sitting upon a chair, the suspender is not materially tensioned and furthermore the pull therefrom is in line with or slightly below the arms 4 and hence has no tendency to lift or swing the lower limb or member upward and forward.

In order that the arms 4 may be utilized as stops for arresting the lower limb or member when it swings back to normal or straightened position, the upper member is

slightly enlarged or swelled to provide downwardly facing shoulders 12 against which said arms shall abut, and to avoid any clicking or noise through this engagement, 5 strips of leather or other cushioning material 13 are secured upon said shoulders for direct contact with the said arms.

From the foregoing it will be apparent that I have produced a knee joint for artificial legs which can be used with either 10 upper or lower amputations, and which combined with suspenders, give full control of the lower member or limb, and which furthermore are serviceable for upper amputations where the upper member is made hollow for its full length, and while I have 15 illustrated and described the preferred embodiments of the invention it is to be understood that it is susceptible of minor changes 20 without departing from the principle of construction involved or the spirit and scope of the appended claims.

I claim:

1. The combination with an artificial limb 25 comprising an upper member and a lower

member, of a knee joint pivotally connecting said members and provided with forwardly projecting arms, and arms extending down from the forwardly projecting arms and secured to the lower member, and suspenders 30 connected at their lower ends to said forwardly projecting arms to be tensioned by the latter when the leg is bent and to utilize said forwardly projecting arms as levers in straightening the leg.

2. The combination of an artificial limb comprising an upper member and a lower member, a knee joint pivotally connecting said members and provided with forwardly projecting arms and arms extending downwardly from the front ends of the forwardly projecting arms and secured to the lower member, the upper member of the limb having exterior downwardly-facing shoulders to constitute abutments for said forwardly projecting arms when the limb as a whole is straightened.

In testimony whereof, I affix my signature.

MILO E. RICE.
